UNITED STATES PATENT OFFICE

2,207,726

APPARATUS FOR TREATING COMPOSITION BOARDS

John Ferla, New York, N. Y., assignor of one-fourth to Paul X. Blaettler, Oaklyn, N. J.

Application February 16, 1937, Serial No. 126,193

2 Claims. (Cl. 101—3)

The invention relates to the art of treating boards of composition material essentially containing asbestos and cement and more particularly to an apparatus for pressing, grooving and trimming a composition board.

It is an object of the invention to provide an apparatus which, in a continuous operation, presses, grooves and trims composition boards.

A further object of the invention is the provision of means for enabling uninterrupted pressing of the board, even though the pressing means become unfit for use.

Another object aims at trimming the board in stages so as to obtain clean severing cuts.

A still further object aims at means for providing grooves in composition boards to enable their assembly in lap-joint arrangement.

Another object aims at providing grooves by a series of forming rollers.

It is also an object to provide certain features of construction and arrangement tending to enhance the utility and efficiency of a machine of the character described.

With these and other equally important objects in view, which will become apparent from a perusal of the invention, the latter comprises the means described in the following specification, particularly pointed out in the claims forming a part thereof, and illustrated in the accompanying drawings, in which:

Figs. 1 and 3 are continuations of each other and illustrate a sectional elevation of the apparatus constructed in accordance with my invention.

Figs. 2 and 4 respectively, are plan views of the construction shown in Figs. 1 and 3.

Fig. 5 is a section on the line 5—5 of Fig. 3.

Fig. 6 is a section on the line 6—6 of Fig. 3.

Fig. 7 is a section on the line 7—7 of Fig. 2.

Fig. 8 is a section on the line 8—8 of Fig. 7.

Fig. 9 is a section on the line 9—9 of Fig. 4.

Fig. 10 is a fragmentary plan view of a modification.

Fig. 11 is a section on the line 11—11 of Fig. 10.

Fig. 12 is a section on the line 12—12 of Fig. 10, and

Fig. 13 is a cross section through a finished board.

In carrying out my invention, the composition board is to be embossed or provided with texture on its surface, thereafter to be provided with a groove along its edges and trimmed to the required size.

As indicated in Fig. 1, the composition boards 10, when produced, are piled on a truck 11 and

supported by metal plates 12, so that in alternate arrangement, the composition board rests on the lowermost metal plate and is below the vertically adjacent metal plate on which again a board rests, and so on until the truck is loaded and brought adjacent to an intermittently operated endless conveyer, generally designated by 14, which comprises a pair of chains 15, 16, trained around gears 17 and 18, and borne by a plurality of small rolls 19 to provide an upper horizontal run 20.

The lower run 21 of the intermittent conveyer is trained around idler gears 22 and adjusting means 23 are provided to maintain the belt in taut relation.

An attendant places the metal plates 12, each carrying a composition board 10, successively onto the conveyer 14 which are brought to a hydraulic press generally designated by 24. The plate 12, with its superposed board 10 being placed above the piston 25, the latter is forced upwardly against an embossing plate 26, (Figs. 1, 7 and 8), mounted to a carrier plate 27 reciprocatingly fitted between guide beams 28, 29 and connected to the piston rod 30 of an air cylinder 31. If the portion of the embossing plate 26, superposed to the piston 25, becomes smudged or covered with foreign substances, then the air cylinder 31 is actuated to cause the plate to move toward the left, as viewed in Fig. 1 until the clean portion of 36 the plate 26 is in alignment with the piston 25.

At each side of the press is an oil pan 32 from which oil is delivered unto rotary brushes 33, adapted to clean the smudged surfaces of the plate 26. After the clean plate portion has been 33 in use for some time, and has become unsuitable, then it is moved to the extreme right position as viewed in Fig. 1, and the unsuitable portion is then cleaned by the rotary brushes at the right of the press 24.

It is, of course, understood that the invention is not predicated on the particular type of press employed, nor on the particular means for cleaning the embossing plate to prevent interruption of the continuous process of pressing and otherwise treating the composition board.

The particular driving means for effectuating intermittent motion of the conveyer 14 is not illustrated as not affecting the invention, as any means suitable or preferred may be employed. 50 The raising of the conveyer by the piston of the press 24 is possible by reason of the adjusting or compensating means 23, as will be readily understood by those versed in the art.

Adjacent to the conveyer 14 is another con-

veyer (Figs. 3 and 4), generally designated by 34, which is continuously actuated and trained around gears 35, 36, and 37. The upper horizontal run 38 of the conveyer 34 is level with the upper run 20 of conveyer 14 by rolls 39 so that the plates 12 and boards 10 are automatically transferred from one conveyer system to another.

5 A roller 40 cooperates with a knife 41 to impart to the board a longitudinal slit 42 which extends approximately midway the thickness of the board and is provided preparatory to execute a severing cut as will be hereinafter described.

10 The conveyer 34 leads to a third conveyer, generally designated by 43, which is trained around gears 44, 45, and 46.

15 The upper run 47 is level with the upper run 38 of conveyer 34 and supported by a plurality of rolls 48. In traveling, the conveyer 43 forces the metal plate 12 and the composition board 10 between three sets of rollers for pressing or forming the grooves on the board 10 (Fig. 13), whereby the same may be arranged in lap joint formation.

20 Of the pair of rollers 49, 49a, the roller 49 is a form roller which imparts to the board 10 a slight groove at the edges and at the center. The next roller pair 50, 50a, and the third roller pair 51, 51a contribute to produce the grooves of desired dimensions.

25 After passing the rollers 51, 51a, circular knives 52, 53 and 54 mounted on a transverse shaft 55 engage the board 10 for the purpose of trimming off the edges of the board and completing the severing cut at the center of the board initiated by the knife 41.

30 Accordingly, at the discharge end of the conveyer, each plate 12 carries two boards and the plates are conducted by a discharge apron 56 onto a truck 57. The boards 10 are provided with grooves or rabbets 58, whereby they may be arranged in interfitting relation so that they may be used as a surface covering of uniform thickness throughout.

35 In the event the boards are not produced by a semi-dry process, but are exceedingly hard, the formation of grooves is carried out in a slightly modified manner.

40 As indicated in Figs. 10 to 12, the grooves are not formed by merely utilizing forming rollers.

which produce the grooves by pressure, but shavings are cut away so as to relieve the necessity of high pressure for extremely hard material.

45 Between the pairs of rollers 49, 49a and 50, 50a, there are interposed pairs of circular knives to cut away a strip at the longitudinal edges of the board.

50 At one edge are a pair of circular knives 59, 60 at right angles to one another and adapted to cut away a rectangular strip; likewise knives 61, 62 cut away a strip at the other edge. The strips are discharged by angle irons 63 into receptacles 64.

55 The knives 60, 62 are mounted on a horizontal shaft 65, while the knives 59, 61 are secured to the upper end of vertical shafts 66, 67, which are geared to a horizontal shaft 68.

60 Attention is called to the fact that the plates 12, when arranged on the conveyers, are held in place by fingers 69 (Fig. 9).

65 While the drawings show preferred embodiments of the invention, numerous changes and alterations may be made without departing from the spirit of the invention.

70 I, therefore, do not limit myself to the details of construction and arrangement, as shown, but wish to include all departures falling within the scope of the invention as defined in the appended claims.

75 I claim:

1. Apparatus for treating composition boards, including an intermittently moving conveyer on which the boards are placed, a press having an embossing plate for imparting texture to the boards while on said conveyer, and means for rapidly shifting said plate to present a clean surface to the board.

80 2. Apparatus for treating composition boards, including an intermittently moving conveyer on which the boards are placed, a press having an embossing plate for imparting texture to the boards while on said conveyer, means for rapidly shifting said plate to present a clean surface to the board, and means for cleaning the used portion of said plate during the operation of said press.

85 JOHN FERLA.
